United States Patent Office

Des. 222,351
Patented Oct. 19, 1971

222,351

CHAIR

George Mergenov, 80 Oaks St., Closter, N.J. 07624

Filed July 6, 1970, Ser. No. 23,826

Term of patent 14 years

Int. Cl. D6—02

U.S. Cl. D15—11

The figure shown is a perspective view of a chair illustrating my new design.

The back of the chair is conventionally plain while the side not shown is substantially identical to the side shown.

I claim:

The ornamental design for a chair, substantially as shown and described.
